(57) **CLAIM**

I claim, the ornamental design for an LED lamp, as shown and described.

DESCRIPTION

FIG. 1 is a top right front perspective view of a first embodiment of the LED lamp showing my new design; FIG. 2 is a top plan view thereof; FIG. 3 is a front elevational view thereof; FIG. 4 is a rear elevational view thereof; FIG. 5 is a left side elevational view thereof, the right side elevational view being the mirror image thereof; FIG. 6 is a bottom plan view thereof; FIG. 7 is a top right front perspective view of a second embodiment of the LED lamp showing my new design; FIG. 8 is a top plan view thereof; FIG. 9 is a front elevational view thereof; FIG. 10 is a rear elevational view thereof; FIG. 11 is a left side elevational view thereof, the right side elevational view being the mirror image thereof; FIG. 12 is a bottom plan view thereof; FIG. 13 is a top right front perspective view of a third embodiment of the LED lamp showing my new design; FIG. 14 is a top plan view thereof; FIG. 15 is a front elevational view thereof; FIG. 16 is a rear elevational view thereof; FIG. 17 is a left side elevational view thereof, the right side elevational view being the mirror image thereof; and, FIG. 18 is a bottom plan view thereof.
The broken lines in the drawings illustrate portions of the LED lamp which forms no part of the claimed design.
